UNITED STATES PATENT OFFICE.

ROBERT M. JOHNSON, OF HAINESPORT, NEW JERSEY.

DESIGN FOR AN ENVELOP.

SPECIFICATION forming part of Design No. 28,953, dated June 28, 1898.

Application filed May 3, 1898. Serial No. 679,632. Term of patent 14 years.

To all whom it may concern:

Be it known that I, ROBERT M. JOHNSON, of Hainesport, in the county of Burlington and State of New Jersey, have invented and 5 produced a new and original Design for an Envelop, of which the following is a full, clear, and exact description.

Reference is to be had to the accompanying drawing, forming a part of this specification, 10 in which the figure is a rear view of an envelop embodying the features of my design.

The design consists in an envelop the free edge of the sealing-flap whereof is provided at one end with a lip which forms a continuation 15 of the free longitudinal edge of said flap and which meets a corner of the body of the envelop at which the flap is attached.

The sealing-flap B of the envelop extends from end to end of the body A of the envelop,

and the free edge b of the flap at one end 20 thereof is interrupted in its general contour by a projecting lip b', which lip commences at the upper point or corner of the body and increases in depth as it leaves that portion of the body of the envelop to which the flap is 25 attached. The lip terminates at a point between the center of the sealing-flap and a point near an end of the same. The flap is not interrupted in its general contour except by the said lip. 30

I claim—

The design for an envelop herein shown and described.

ROBERT M. JOHNSON.
